FOUNTAIN PEN

Filed Sept. 10, 1938

UNITED STATES PATENT OFFICE

2,187,160

FOUNTAIN PEN

Laura Kohler and Arthur Kohler, Chicago, Ill.

Application September 10, 1938, Serial No. 229,363

9 Claims. (Cl. 120—47)

This invention relates to fountain pens and the object thereof is to provide a novel construction of fountain pen and filling device therefor which eliminates the usual rubber sack as an ink containing reservoir and also lateral compression or flattening thereof in filling the ink chamber of the pen, thereby eliminating an objectionable feature which usually quickly renders the sack and pen useless by causing the sack to remain flat in such a manner as to prevent filling due to its deflated condition and renders the same incapable of expanding and drawing in ink so that the pen is rendered useless.

Another object of the invention is to provide means for protecting working parts of the device generally from contact with the ink, and to provide a novel arrangement of vents and passages to facilitate filling with increased capacity as well as to provide an actuating cap which is held down during the normal use of the pen or when the ink chamber or reservoir is filled, and which is in a raised position when disconnected for depression thereof in filling the ink chamber with ink.

Other objects and advantages will become apparent and be brought out more fully in the following specification, wherein:

Fig. 1 is a sectional elevation of a fountain pen in accordance with the invention with the filling cap raised;

Fig. 2 is an enlarged fragmentary sectional view of the upper portion of the pen with the parts in the same position as shown in Fig. 1;

Fig. 3 is a view similar to Fig. 2 but showing the filling cap partly depressed in the act of filling the pen;

Fig. 4 is a similar view showing the cap held down on the barrel of the pen after the filling has been completed;

Figs. 5 and 6 are sectional views taken on the lines 5—5 and 6—6 of Fig. 2;

Figs. 7 and 8 are enlarged sectional views taken on the lines 7—7 and 8—8 of Fig. 1;

Fig. 9 is a fragmentary elevation of the upper portion of the pen; and

Fig. 10 is a fragmentary vertical sectional view of the lower portion of the pen and pen point at right angles to Fig. 1.

Referring more particularly to the drawing, the pen is shown as comprising an outer barrel 15 and an inner barrel 16 having an ink chamber or reservoir 17, the inner barrel snugly fitting the outer barrel. The lower end of the outer barrel receives a spud 18, the latter having an externally screw threaded portion fitting an

internally screw threaded portion of the open lower end of the outer barrel as shown at 19. The reduced threaded portion of the spud 18 produces an upwardly facing annular shoulder 20 which abuts the lower end of the outer barrel. A throat member 21 is formed at the lower portion of the spud which latter has an upwardly facing annular shoulder 22 at the top formed by a reduced portion 23 with a tapered recess 24 centrally at the top thereof. The throat member has a central opening or bore 25 receiving a pen point or nib 26 which is held in position by a plug 27 having a feed bar 28 provided with a feed channel 29 adjacent the point. A passage or duct 30 extends up through the spud in line with the channel 29 to the ink chamber 17. Air vents 31 are provided between the inner and outer barrels, the same being formed by grooving the inner barrel longitudinally with parallel semicircular grooves 31 shown equidistantly spaced apart around its periphery and running the length thereof for communication with an annular channel 32 at the bottom. Two ducts 33 extending longitudinally of the spud and throat portion are placed in communication with the air vents 31 at diametrically opposite sides through the medium of curved portions 34 shown more particularly in Fig. 8 of the drawing and having outlet air ducts 35 extending to the lower end of the throat member.

A piston 36 operates in the cylindrical chamber of the inner barrel 16 near the top thereof and has a sleeve portion 37 with a plurality of peripheral grooves receiving packing rings 38 preferably three in number so as to form a seal at this point. The head of the piston is provided with a tapered passage 39 forming a valve seat with which cooperates a tapered headed valve 40 carrying a weight 41 on the depending stem thereof normally closing the valve. The sleeve 37 which extends upwardly from the head of the piston has a pair of diametrically opposed internal arcuate recesses 42 communicating with longitudinal passages 43 similarly related and extending up through the wall of the sleeve to the top end thereof for communication with a chamber 44 above the upper end of the inner barrel and within the outer barrel. A reduced externally threaded portion 45 of a removable tubular upper part 46 of the barrel has threaded engagement with internal threads at the upper end of the outer barrel 15 as shown at 47. A piston including a head 48 is positioned within the sleeve 37 of the piston 36 and receives in a central bore at the top thereof, the lower sec-

tion 49 of a plunger rod having an enlargement or piston 50 at the top formed with a tapered recess 51 in the upper end thereof and producing a shoulder beneath. A tapered enlargement 52 is formed at the lower end of the upper section or shank 53 of the plunger rod and a cap 54 preferably knurled as shown in Figs. 1 and 9 is secured or fixed on the upper end of the section 53 and is counterbored at the bottom and provided with a small inwardly extending lug 55 adjacent its bottom edge. A reduced part 56 of the removable upper part 46 of the barrel forms an annular rib at the top by reason of an annular groove 57 spaced from the upper end thereof and this rib has a longitudinal slot 58 communicating with the groove 57 designed to receive the lug 55 for the purpose of holding the cap down on the barrel or releasing the same to be elevated in spaced relation thereto for filling the pen as will be further described. A flexible soft rubber sack 59 receives the piston head 48 and fits in a reduced bore 60 of the part 46 at the upper end of the latter and over a tubular part 61 of a hard rubber or metallic sleeve 62 having a thickened wall at the top received within an enlarged counterbore of the section 46 immediately above the reduced bore portion 60 and seating on an internal upwardly facing annular shoulder 63 produced thereby. The sleeve 62 has an annular groove 64 within the bore portion 60 and this peripheral groove receives the wall of the soft rubber sack or protector 59 which is depressed into the groove through the instrumentality of a contractile spring ring or retainer 65 which seats in a groove and securely connects the sack to the tubular part 61 of the sleeve 62. The sleeve serves to permit stretching of the sack thereover and has an apertured bottom 66 receiving the lower section 49 of the plunger rod therethrough for connection to the piston 48 and serves as a holder for a spring 67, the lower end of which seats on a brass or like packing ring 68 and the upper end of which correspondingly seats on an upper packing ring 69. The lower packing ring is disposed against the bottom 66 and the upper packing ring against the bottom shoulder of the enlargement 50 so that the spring normally tends to raise the plunger and cap. These parts are held from displacement entirely by means of a retaining ring 70 fitted in the internal bore of the sleeve 62 and snugly receiving the plunger rod 53 therethrough although any air which may be within the sleeve 61 and the sack 59 may escape between the bore of the sleeve and the parts 50, 52 and 70 so as to vent the interior of air and therefore eliminate a dash pot or cushion.

In the operation of the device in filling the ink chamber, the cap 54 is turned in the groove 57 beneath the rib 56 until the lug 55 is beneath the slot or groove 58 whereupon the cap will be elevated assisted by the tension of the spring 67 expanding and forcing upwardly on the piston 48 against the shoulder at the bottom of the enlargement 50 of the plunger and consequently elevating the enlargement 52 beneath the ring 70 so that the cap will be in the positions shown in the Figs. 1, 2 and 9 of the drawing. This, of course, will permit the sack 59 to contract and the piston 36 and its sleeve 37 will be upwardly displaced within the bore of the inner barrel 16 forming the ink chamber or reservoir 17. The pen is then inserted in the well of ink and by forcing downwardly on the cap to the position shown in Fig. 3 and stretch-

ing the sack or protector 59, the piston 36 will also be forced downwardly to compress the spring 67 and the air beneath the piston 36 which will unseat the valve 40 and permit the air to escape through the passage 39, passages 43 and through chamber 44 and air vents 31 to the annular channel 32 and openings 34 from the passages 33 and out through the outlet air ducts 35. During this time, ink will pass up through the feed channel 29 and passage 30 to the ink chamber or reservoir 17 so as to expel all air from the latter and sufficient displacement is provided to permit the ink to pass into the passages 43 and 31 although this is not preferred. By further downward pressure on the cap, the spring 67 will be compressed further as shown in Fig. 4 and to further distend the sack 59, whereupon the lug 55 may be passed through the groove 58 and beneath the annular shoulder formed by the groove 57 beneath the portion 56 constituting an annular rib peripherally around the reducing upper portion of the sack 46, thus holding the cap down against the top of said sack 46. Upon emptying of the ink in the chamber, the cap may be disconnected and will be elevated by the spring 67 upon the lug 55 aligning with the groove 58 so that the filling operation may be simply and effectively accomplished. Of course, the valve 40 will normally return to a closed position when the pressure of the air within has been released by the displacement thereof and the piston 36 will give a large area of displacement with a short stroke within the bore of the inner barrel 16 while the sack will prevent the ink from escaping through the top portion of the pen and leaking at this point. At the same time, the parts are such that they can be easily and economically produced and readily assembled in the complete structure at a minimum of cost.

While I have illustrated and described the preferred form of construction for carrying my invention into effect, these are capable of variation and modification without departing from the spirit of the invention. I, therefore, do not wish to be limited to the precise details of construction set forth, but desire to avail myself of such variations and modifications as come within the scope of the appended claims.

Having thus described our invention, what we claim as new and desire to secure by Letters Patent, is:

1. In a fountain pen, a barrel having an ink chamber, means for filling said chamber including a piston operating in the ink chamber, a plunger operating in the piston, a sack anchored to the barrel and extending between the piston and plunger for expansion or retraction by the plunger, and means for sealing the latter means and closing off the same including said sack and a rigid sleeve in the sack and anchored to the barrel.
2. In a fountain pen, a barrel having an ink chamber and a filling opening, pistons for filling the chamber, and means for permitting movement of the pistons in filling the chamber and cutting off the passage of ink past the pistons, said pistons being positioned on opposite sides of the last named means.
3. A fountain pen comprising a barrel having an ink chamber, an inlet for ink leading into the chamber and air vents for discharging air from the chamber upon being displaced by ink, a plunger movable in the chamber to draw ink into the latter and expel the air therefrom, a

5 sack mounted in the barrel and stretchable during the movements of the plunger, said sack sealing the interior of the chamber from the exterior, a tubular member closing the top of the barrel, a second plunger movable in the barrel and tubular member within the sack and means for actuating the plunger.

10 4. A fountain pen comprising a barrel having an ink chamber, an ink inlet and air vents for air displaced by the ink entering the chamber, a plunger movable in the chamber, a valve in said plunger, an extensible sack within the barrel and extending into the plunger, and a second plunger movable in the sack.

15 5. A fountain pen comprising a barrel having an ink chamber, an ink inlet and air vents for air displaced by the ink entering the chamber, a plunger movable in the chamber, a valve in said plunger, an extensible sack within the barrel 20 and extending into the plunger, a second plunger mounted within one end of the sack and movable to expand the same, said second plunger being mounted in the first plunger for actuating the same, and means for holding the second plunger 25 in an extended position.

25 6. A fountain pen comprising a barrel having an ink chamber, an ink inlet and air vents for air displaced by the ink entering the chamber, a plunger movable in the chamber, a valve in said plunger, an extensible sack within the barrel 30 and extending into the plunger, a second plunger mounted within one end of the sack and movable to expand the same, said second plunger being mounted in the first plunger for actuating the same, said valve being weighted, said second 35 plunger being separated from the interior of the barrel by the sack, a cap on the second plunger, and means for connecting the sack to the barrel.

35 7. A fountain pen comprising a barrel having an ink chamber, an ink inlet and air vents for air displaced by the ink entering the chamber, a plunger movable in the chamber, a valve in said plunger, an extensible sack within the barrel 40 and extending into the plunger, a second plunger mounted within one end of the sack and movable to expand the same, said second plunger

being mounted in the first plunger for actuating the same, said valve being weighted, said second plunger being separated from the interior of the barrel by the sack, a cap on the second plunger, 5 means for connecting the sack to the barrel, said second plunger comprising sections, a spring holder within the sack, and a spring in the holder and acting on the second plunger to protect the same from the barrel, and means to prevent displacement of the second plunger. 10

8. A fountain pen comprising inner and outer barrels with air vents therebetween, a point holding member held in the outer barrel against the inner barrel, said member having an ink feed channel leading into the inner barrel and air 15 ducts leading to the vents, a sleeved piston movable in the upper portion of the inner barrel and having air passages between the inner barrel and said vents and a passage having a seat, 20 a weighted valve normally closing said seat, a stretchable sack in the piston and anchored in the barrel, a two part plunger having a head in the sack within the piston, a rigid sleeve held in the outer barrel and receiving the plunger through its lower end within the sack, a spring 25 in the sleeve normally holding the plunger projected from the outer barrel, and means coacting between the plunger and outer barrel to hold the plunger down.

9. A fountain pen comprising a barrel having 30 an ink chamber, an inlet for ink leading into the chamber and air vents for discharging air from the chamber upon being displaced by ink, a plunger movable in the chamber to draw ink into the latter and expel the air therefrom, a 35 sack mounted in the barrel and stretchable during the movements of the plunger, said sack sealing the interior of the chamber from the exterior, a tubular member closing the top of the barrel, a second plunger movable in the barrel 40 and tubular member within the sack, a cap having a shank with an enlargement held from displacement with respect to the barrel, and means for securing said cap to the barrel.
